UNITED STATES PATENT OFFICE.

ALFRED BREDBERG, OF CHAMPLAIN, NEW YORK, ASSIGNOR OF ONE-HALF TO THE SHERIDAN IRON WORKS, A CORPORATION OF NEW YORK, AND ONE-HALF TO T. W. & C. B. SHERIDAN COMPANY, A CORPORATION OF NEW YORK.

BOOKBINDING-MACHINE.

1,129,064.

Specification of Letters Patent. Patented Feb. 23, 1915.

Application filed March 23, 1911. Serial No. 616,393.

To all whom it may concern:

Be it known that I, ALFRED BREDBERG, a citizen of the United States, and a resident of Champlain, Clinton county, New York, have invented certain new and useful Improvements in Bookbinding-Machines, of which the following is a specification.

The present invention relates to book binding machines and more particularly to those machines in which groups of leaves or signatures which are to constitute the books are presented consecutively to instrumentalities designed to operate thereupon for performing one or more of the different steps in the binding and covering of pamphlets, magazines or other books.

The invention has for an object to provide improved mechanism for the purpose of performing certain of the operations involved in the course of binding and covering; and more particularly to provide an efficient and reliable mechanism for applying a strip of crash or other fibrous material to the adhesive covered backs of books, pamphlets and the like.

Other objects will appear hereinafter in the following description or will be obvious therefrom.

The invention consists in the novel parts, improvements, mechanisms, combinations and arrangements herein shown and described and set forth in the claims.

The accompanying drawings referred to herein and forming a part of this specification, illustrate one embodiment of the improvements, the same serving in connection with the description to explain the principles.

In the drawings, Figure 1 is a front view of a book binding machine, or a sufficient portion thereof to illustrate the principles of the present invention, certain mechanisms being omitted to which the present improvements are not specifically directed, but which can be supplied by reference to prior application Serial No. 292,407, filed on or about Dec. 19, 1905. Fig. 2 is a right end elevation of the parts seen in Fig. 1. Fig. 3 is a similar view of certain parts of the strip handling mechanism detached from the other parts shown in Fig. 2 and indicated in a different position or stage of operation. Fig. 4 is a left-hand elevation of a detail of the construction shown in Fig. 1.

Fig. 5 is a rear elevation of the strip feeding 55 rollers. Fig. 6 is a front elevation of the strip cutting devices. Fig. 7 is a right-hand elevation illustrating the strip feeding devices on an enlarged scale. Fig. 8 is a plan view of a detail.

In the class of machines illustrated, there are a series of holders carrying books and connected to an endless device so that each holder travels from place to place in the machine bringing the book successively to the different mechanisms which are to operate on it. For example, the mechanisms may apply adhesive and then attach a narrow fibrous or textile strip to the moist adhesive and afterward apply a cover. The strip 70 aids in more efficiently securing permanent connection between the different leaves and the cover.

In the present invention there is a strip applying mechanism in which the fibrous 75 strip is adjusted to the book and then impelled reliably into position without mechanical pressure or contact between the applying mechanism and the adhesive covered part of the book. The strip might be constituted of cotton batting, crash, cloth or possibly paper. If this were mechanically pressed into place, adhesive would pass to the pressing part which would destroy its efficacy.

The desired objects are accomplished herein by the use in combination with the other parts of a pneumatic means for impelling the strip by air flow to move into position, thus obviating mechanical pressure; and with this pneumatic mechanism is combined means for feeding fibrous material and cutting off strips as required for successive books. Specifically, the strip holder hereof has hollow passages with openings adapted 95 to be directed toward and in proximity to the adhesive covered portions of the book; and means for controlling the air flow, preferably so that the strip is first retained by suction until justified in proper position, 100 the air flow being then reversed and compressed air issuing to forcibly drive the strip across the gap into place on the book.

The strip holder is preferred to be vibratable between a strip receiving position and a strip applying position adjacent to the book.

The above and other features of the inven-

tion will be more particularly set forth in the following description.

Referring now in detail to the particular embodiment of the invention illustrated in the drawings, some of the main portions of the machine, as to which *per se* no claim of novelty is herein directed, will first be described and then the novel mechanism illustrating the present invention will be set forth.

In the first place the machine has a frame A carried on a base A'. Certain specific frame parts that coöperate with the strip handling mechanism will be hereinafter described in connection with the latter. In the upper part of the frame are upper guides B and lower guides B' shown in the form of channels with flanges turned toward each other adapted to receive between them traveling parts shown in the form of slides B², each of which slides, together with the book-holding-clamp to be described, may be considered as a carrier. As is usual there may be an extended series of such book carriers traveling one behind another around the guides or tracks B, B', and as before stated said guides may form a continuous or endless track so that on completing the cycle each carrier stands at the position ready to commence a new cycle. One arrangement by which this last named result has been accomplished is to form the carrier track in two long straight stretches, one on each side of the machine and the two stretches connected to each other at the ends by curved or irregular track portions; this arrangement being indicated in Fig. 2 of the drawings by the showing of tracks B, B', at the rear of the machine, within which is one of the book carriers comprising slides and clamps. With such extended length of travel of a book carrier each book may be subject to any desired number of operations by any desired number of mechanisms comprised in or mounted on the same machine, and the nature of the appropriate mechanisms to be so employed, has been hereinabove indicated; only sufficient of the machine, however, being actually illustrated in the drawings hereof to enable a complete disclosure to be made of the improvements sought to be covered herein. On the outside of each of the slides is a suitable clamp comprising a front clamp part C and a rear clamp part C', the reference Z representing the book or more correctly speaking the group or collection of leaves or signatures which are to be constituted into a book, pamphlet or the like. The springs or other means for pressing toward each other the two clamp parts C, C', are not shown as these will be well understood. The several carriers, of which five are indicated in Fig. 1, are not in the drawings hereof connected to each other, and for the purposes of the present improvements they

need not be connected, as each carrier containing book Z may be moved onward by hand to the mechanism embodying the present improvements, the track or guides constituting a means for or aid in positioning the book. It will, however, be understood that the carriers may be flexibly connected one to another in a train, so that a driving mechanism may be employed for simultaneously advancing all of the carriers, and so as to successively bring each of the books into operative position in each of the different mechanisms constituted in the machine.

The portions of the mechanism to which the present improvements more particularly relate will now be described, it being understood that, by means of an automatic adhesive applying mechanism or otherwise, a portion of each book or leaf-group, namely the back edge portion, has been moistened with adhesive before the operation upon such book of the mechanism of the present invention.

A strip holder indicated generally by D is one of the elements of the illustrated embodiment of the invention, it comprising a to and fro moving member or frame D' mounted for convenience to turn about a shaft or shafts D² enabling it to oscillate to and fro. In operation the fibrous strip indicated at y is supported or held at the extreme upper portion of the strip holder D as seen in Fig. 2, and it is in the position shown in this figure that the mechanism is adapted to operate for applying the fibrous strip to the adhesive covered edge, that is the lowermost edge as shown, of the book Z.

Generally speaking the strip holder may be said to vibrate between the strip applying position shown in Fig. 2 and the strip receiving position, clearly indicated in Fig. 3; the material which is to form the strip being in the latter position both fed on to the strip holder and severed.

The strip holder and its operating mechanism and adjuncts including the air compression and suction control will first be described, and thereafter the strip cutting and feeding mechanism will be considered.

The strip holder D comprises in addition to its frame D' a head d at the upper end. This is the important part and that upon which the strip is actually held or supported until its application to the book. The head d is movably connected to the frame D' for purposes that will hereinafter appear, this being accomplished through a pair of vertical guide rods d' passing through upper rod bearings d² and also rod bearings d³ consisting of simple cylindrical holes in the frame D'. The natural tendency of the head d is to move downward but it may be moved upward to different points by certain mechanism to be described. This mechanism includes a cam d⁴ mounted upon a

longitudinal shaft X, which shaft may be considered the main driving part of the machine, it having cams and connections by which the several operations of the machine are performed automatically in improper order. Shaft X may be power driven by a pulley or any other convenient means. The cam d⁴ operates a train of mechanism or connections of which the last element engages a roller d⁵ secured or clamped by a device d⁶ upon the vertical rod d'. Bearing against the roller d⁵, see Figs. 2 and 3, is a swinging member d⁷ mounted on a shaft d⁸ having a fixed position in the machine, and the member d⁷ has an upper surface d⁹ upon which the roller d⁵ may roll when the two are in operative contact. A link d¹⁰ is connected at its lower end to member d⁷ and at its upper end to one arm d¹¹ of a bell crank lever mounted on a shaft d¹² having a fixed position in the machine, the other arm d¹³ of the bell crank lever being connected to an irregularly shaped rod d¹⁴, whose conformation is unimportant except to enable it to clear the other machine parts when in operation. The other end of said rod is guided in its to and fro movements by an oscillating arm d¹⁵ pivoted to a shaft X' having a fixed position in the machine; and the extreme end of the rod d¹⁴ is provided with a bearing surface such as the cam roller d¹⁵⁰ adapted to bear directly on the cam d⁴ previously mentioned. The parts are kept in engagement by means of a spring which may for convenience be located at d¹⁶. The cam d⁴ has four important surface portions, namely: d¹⁷, the function of which is to present the strip holder head d to the strip-forming mechanism, as in Fig. 3; portion d¹⁸, shown in operative position in Fig. 2, and serving to hold the head d in position for applying the strip y to the book Z; and d¹⁹ and d²⁰, which move the head d from one position to the other, and in doing so cause it to pass to a third and lower position and thus approach and recede from the plane in which the strip is formed in a direction transverse to that plane.

As shown, the mechanism for causing the to and fro movements of the strip holder consists of an adjustable arm D³ extending from a lug D⁴ formed on the strip holder frame to the upper end of a lever D⁵ whose lower end is pivoted upon a shaft X² having a fixed position in the machine. Adjustably connected to the arm D³ is a rod D⁶, its adjustment comprising a sliding block arrangement D' with adjusting screws D⁸ for determining the position of the block and thereby regulating the effect that the rod's movement will have upon the strip holder. The right-hand end of the rod D⁶ is provided with a roller D⁹ which bears against a cam D¹⁰, mounted on the same driving shaft X that carries the cam d⁴. To guide the end

of the rod D⁶ which carries the roller D⁹ a swinging arm D¹¹ is shown as connected at its upper end to the rod and at its lower end mounted upon the same shaft X' upon which arm d¹⁵ is mounted. A spring D¹² under tension extending from arm D¹¹ to a lug D¹³ on the arm D⁵, serves to pull arm D⁵ toward the right in Figs. 2 and 3, and thereby cause the roller D⁹ to constantly press against the surface of its cam D¹⁰. Cam D¹⁰ has a portion D¹⁴, which is in operative position in Fig. 2 and serves to hold the rod D⁶ and the strip-holder D in the vertical position shown; and a portion D¹⁵ which is seen in Fig. 3 to have permitted rod D⁶ and the strip holder D to move toward the right. In this way the cam D¹⁰ effects the oscillating movement of the strip holder between strip applying position and strip receiving position, the latter being shown in Fig. 3.

In referring to the air controlling apparatus the invention in its broader aspects is not limited to air as other fluids may in whole or in part be available, and various means may be employed to render the same effective to produce the desired results. In the embodiment illustrated a control valve E is employed which has two or more positions, one position adapting it to connect the strip holder with a suitable compressed air supply, and another position with a suitable exhausting means. The sources of compression and suction do not need to be shown in detail as they may be of any convenient type to produce air outflow and inflow. However, the pipe E' may be considered as a source of exhaust and the pipe E² as a source of compression, or a rotary blower could well be employed for both functions. Both of the pipes E', and E² extend as shown to the valve E and there extends in turn from the valve a pipe E³ to which is coupled a flexible pipe or hose e, the other end of hose e leading to the hollow interior of the strip holder head d through a pipe e'. The hollow head d shown in end view in Fig. 2 is seen in front view in Fig. 1, and in that figure is indicated in dotted lines the construction of the interior passages. Thus it shows a longitudinal passage e² extending from end to end, its ends being plugged, and showing a series of seven vertical passages e³, each having a small nipple or nozzle at its upper terminus, the passage in which leads outward to the atmosphere. In this way a series of openings which may be of any number and arrangement are provided in the otherwise flat topmost surface of the head d, thus enabling either suction or compression to be applied to the fibrous strip supported on the head. It should be here mentioned that the purpose of the suction or inflow is to operate prior to the application of the strip to the book for the pur-

pose of securely holding the light material in its proper position on the strip holder and obviate its accidental displacement. The purpose of the compression is that a forcible outflow of air (preferably in jets) may be caused to lift and bodily move the strip from its position upon the strip holder upward to its proper position upon the adhesive covered portion of the book, and to exert a sufficient pressure upon the strip to cause it to stick reliably to the adhesive and be thus united to the book so as to be carried thereby to the place where the cover is applied. Since no mechanical pressure is exerted upon the strip when in contact with the adhesive, littering and clogging up the parts of the strip handling mechanism with adhesive matter from the books is avoided. The presence of the fibrous strip not only more firmly binds together the back edges of the leaves, but also aids in uniting the group of leaves to the cover subsequently applied.

The valve E may be of any suitable construction, adapted to alternately connect the pipes E' and E² with the pipe E³. As shown the valve has a stem e⁴ with an arm e⁵ thereon, the arm having actuating means including a rod e⁶ extending as seen in Figs. 2 and 3 toward the right, its extremity having a roller e⁷ contacting with a cam e⁸ mounted upon the same driving shaft X that carries the cams d⁴ and D¹⁰. The configuration of cam e⁸ is such as to cause the movements of the valve arm e⁵ to operate the valve in harmony with the other parts of the mechanism. Cam surface e⁹ briefly opens compression pipe E², while surface e¹⁰ holds the valve in position to open exhaust pipe E', and surface e¹¹ holds the valve in position to open exhaust pipe E', and surface e¹¹ holds the valve in position to close both pipes. A spring e¹³ may be so arranged as to pull downward upon the valve arm e⁵ for the purpose of keeping the parts under the influence of the cam e⁸. The cam revolves in the direction of the arrow. The compression surface e⁹ is seen to immediately follow the suction surface e¹⁰ so that the air flow is abruptly reversed. The valve momentarily passes through suction position when the roller e⁷ passes from surface e⁹ to surface e¹¹ and remains closed until e¹¹ is again replaced by suction surface e¹⁰ just prior to the dropping of head d and the swinging of the strip holder from right to left.

By way of introduction to a description of the strip cutting and feeding mechanisms, reference will first be made to so much thereof as is shown more or less diagrammatically in Fig. 3. The strip y is shown as not yet severed from the roll or supply Y, but as being cut or about to be cut by a suitable cutting mechanism. As

shown, this mechanism comprises an upper knife F and a lower knife f, they being adapted to coöperate by suitable mechanism which will be described. In Fig. 3 the strip y is shown as compressed or held between the knife F and the strip holder D, the head d of the latter having an up and down movement as already explained, enabling it to be moved upward to the position shown with a portion of the fibrous material between it and the knife F. The knife f is preferably a rotary one, it being secured upon a suitably mounted shaft f' which is also provided with a gear f² of substantially the same size as the knife. The gear meshes with a rack f³ so that as the knife f is moved along the knife F as presently described, the former will be rotated, thus severing the strip y from the body Y of the fibrous material. The material Y coming from the spool passes in the direction of the arrow Fig. 3, and moves forward between the main feed roller G and a coöperating roller g, there being a supplemental small roller g' for the purpose of giving the fibrous material greater extent of contact with the main feed roller G. And thereafter the material passes to the left between a pair of small roller g², g³ located in close proximity to the knives F, f, said rollers g², g³ being driven through an intermediate gear g⁴ which in turn is driven by the rotation of the main feed roll G.

The feeding mechanism partly seen in Fig. 3 has its details shown in Figs. 4, 5 and 7, Figs. 1 and 2 showing it as a part of the completely assembled machine. The main feed roller G is on a shaft g⁵ which has bearings in a fixed frame part g⁶, there being a complementary frame part g⁷ at the opposite end of shaft g⁵. Directly beneath the feed roll G is feed roll g on shaft g⁸ journaled upon two vertically slid able members g⁹ extending through suitable holes in frame parts g⁶ and g⁷ and emerging therefrom to pass through coil springs g¹⁰ which are held under compression by washers or collars g¹¹ located near the top of members g⁹ and confined in place by pins g¹², this arrangement serving to yieldingly press roller g up against roller G. These rollers constitute the principal part of the feeding mechanism and the material receives its travel from them. Their illustrated construction is peculiar, and is superior for feeding such materials as have been referred to. Such construction is best seen in Fig. 5 in which roller G is seen to have a series of raised contact surfaces g¹³ in the nature of more or less broad flanges or circumferential ribs whose outer circumferences are roughened or milled to prevent slipping of the material, and between the surfaces g¹³ are substantial spaces; this construction being superior for feeding such materials as have

been referred to. On roller g opposed to the raised contact surfaces g^{18} are a series of milled or roughened circumferential portions g^{14} between which are shown smooth 5 separating surfaces.

The rollers g^2, g^3 previously referred to are seen in Fig. 7 where they are indicated as geared together by gears g^{15}, g^{16} and g^4 , the last named being mounted on a shaft g^{17} 10 and geared to a gear g^{18} mounted on the same shaft g^5 that carries the main roller G , so that all of these rollers are driven at the same surface speed.

There is a great advantage in having in 15 addition to the large or main feed roll a pair of small positively driven feed rolls such as g^2, g^3 for the reason that such small rolls may be brought into position closely adjacent to the cutting knives. The material is 20 often extremely sleazy or flimsy and needs to be supported up to the point where it is actually delivered to the strip holder and severed.

Adjusting means are shown for vertically 25 adjusting the position of the rolls g^2, g^3 , they and the gear g^4 being all mounted on vertically sliding members g^{19} which pass alongside the fixed frame parts g^6 and g^7 and at their upper ends are provided with 30 screw adjusting devices g^{20} for the purposes referred to. Only one of the members g^{19} and, adjusting screws g^{20} is illustrated (in Fig. 7) but it will be understood that these parts will be duplicated at the opposite ends 35 of the rollers. As shown, the screw g^{20} has two flanges g^{21} , one below the other, and between said flanges project two lugs each forming a part of the member g^{19} . When the handle g^{23} of the screw is turned the 40 screw is driven down into the body of the frame part g^6 and its flanges carry down the lugs g^{22} and with them the member g^{19} carrying the feed rolls g^2, g^3 .

For driving the feed mechanism any 45 convenient means may be adopted, for example a pawl and ratchet adapted to give a step by step motion. Thus in Fig. 5 a ratchet g^{24} is seen at the right end of shaft g^6 . A pawl g^{25} engages ratchet g^{24} , this pawl being seen 50 in Figs. 2 and 4, in the latter of which figures it is seen to be pivoted at g^{26} to an arm g^{27} of a lever pivoted to a shaft X^4 having a fixed position in the machine. The other arm g^{28} of the lever has pivoted to its extremity a rod g^{29} which extends downwardly 55 as shown in Figs. 1 and 2, and is conveniently connected to an oscillating arm g^{30} secured on the same oscillating shaft X^2 that carries the arm D^5 hereinbefore referred to as 60 constituting part of the strip-holder vibrating mechanism, so that the oscillation of the shaft will operate the pawl g^{25} and advance the ratchet wheel step by step. The degree of movement of the ratchet wheel may be varied so as to feed a strip proportional to the 65

width of the books in any suitable way. As shown the rod g^{29} is connected to the arm g^{30} by a block g^{31} which is adjustable on the arm as by means of a screw g^{32} so that the extent of movement of the rod may be varied. 70

Figs. 2 and 4 show a handle H whose purpose is to throw the pawl g^{25} out of operation when it is desired to stop the feed; this handle being pivoted at its lower end to a fixed frame part h and having pivoted at an intermediate point a rod h' which extends therefrom to the pawl g^{25} . The handle is capable of being thrown forwardly or backwardly and when in the rearward position 80 seen in Figs. 2 and 4 and also seen in Fig. 8, the pawl is operative. When the handle is reversed or thrown forwardly the pawl is lifted out of operative position. The handle is held in this position by a spring h^2 , Figs. 85 2 and 8, attached to a fixed frame part h^3 , having a slot at h^4 in which the handle moves. As shown, the handle also serves when moved forwardly to lock the shaft X^2 against movement by the spring D^{12} and 90 thus hold the strip holder in its forward position and render it inoperative.

The strip cutting mechanism is illustrated in detail in Figs. 1, 2, 3 and 6. The shaft f' of lower rotary knife f has bearings upon a 95 to and fro moving slide f^4 , the said shaft f' , it being remembered, having gear f^2 at its far end automatically rotated by engagement with rack f^3 as the knife f is moved along the knife F . The slide f^4 may rest upon a fixed guide f^6 and have a dove-tailed engagement therewith. Beneath and supporting guide f^6 is a web f^{18} which connects the guide with a horizontal base portion f^{17} which in turn is mounted on a pair of fixed 100 frame parts f^{18} . The slide f^4 is caused to travel to and fro by the following mechanism: A pitman f^6 is pivoted at f^7 to the slide f^4 , the other end of the pitman as seen in Fig. 1 being connected to the upper end 110 of an arm f^8 which is secured to shaft X^3 , having a fixed position in the machine. The connection between the two may be such as to permit disconnection at will by merely lifting the horn f^9 forming an extension of 115 pitman f^6 , the latter being constructed with a slot which drops over the pin f^{10} in the yoke f^{11} of the arm f^8 for affording such detachable connection. A powerful spring f^{12} secured at one end to arm f^8 and at its other 120 end to a fixed part of the machine gives a tendency in the arm and connected parts to move toward the right. For opposing the spring, and imparting oscillating movements to the arm is employed a cam f^{13} mounted on the same shaft X which carries the cam d^4, D^{10} and e^8 . Cam f^{13} acts upon and is contacted by a roller f^{14} mounted upon an arm f^{15} secured to the same shaft X^3 which 125 carries arm f^8 . By this described arrangement 130

ment the rotation of shaft X causes the to and fro movement of the cutter knife f, and its movements will be in harmony with the other parts of the mechanism by the proper positioning and contour of the cam f¹⁸.

Fig. 1 shows the rotating cutter wheel at its left-hand position, and Fig. 6 at its right-hand position. It has been explained that the knife f is compelled to rotate as it travels, and that its relation with the stationary knife F is such as to sever a strip of the material Y. This cutting is done as the knife f moves leftward from Fig. 6 position, and the shape of cam f¹⁸ is such that the knife immediately returns to the right preparatory to a subsequent feeding and cutting operation. The cutting operation in the illustrated mechanism always occurs with the parts in the position seen in Fig. 3 where the extreme portion or strip of material is held between the strip holder and the knife F.

In operating the knives in the manner described the objection results that the unsevered part of the material is forced upwardly by knife f behind knife F where it is likely to remain. Obviously in order to properly feed for the next strip the material must stand sufficiently below the knife F to certainly clear it during the feeding movements. To insure this an auxiliary device for forcing the material downward from the stationary knife is provided. As shown, this clearing device includes a movable member J seen in front view in Fig. 6 and in edge view in Fig. 2. The stationary knife F has two inclined cam grooves or slots at j, j, with which cam pins j' engage, said cam pins being formed or secured on the member J which lies behind the knife F. The normal position of member J is sufficiently high that its lower edge will clear the rotary knife f in its to and fro movements as shown in Fig. 2. When, however, the rotary knife after cutting a strip has passed back to the right as in Fig. 6, the slide f⁴ is caused to strike a projection j² on a lever j³ thus deflecting said lever. The lever is pivoted at j⁴ to a lug or standard j⁵ fixed to a convenient frame part, and the upper lever end is pivoted to a pitman j⁶ which in turn is pivoted at j⁷ to a suitable portion such as the upper projection j⁸ of the member J; a spring j⁹ being employed tending to move the member J toward the right and restore the parts to normal position. This motion communicated by the lever j³ to the member J moving it to the left, causes the cam pins j' to pass downwardly owing to the incline of slots j and thereby the member J is carried bodily downward to the position seen in Fig. 6. In this way the function is performed of restoring the supply of material to a sufficiently low position to be properly fed beneath knife F. When the knife f and

slide f⁴ start toward the left for cutting, the lever j is at once released and the spring j⁹ effects the restoration of member J to its normal position so that it will not interfere with the rotary knife.

The operation is as follows: Starting with the position of Fig. 2 the strip-holder D is in its upright position and the head d is in its fully raised position. At this stage the cam e⁸ operates to move the valve E so as to admit compressed air to the interior of the strip holder and thereby cause a forcible upward current which issues in jets at the top surface of the head d and drives the fibrous strip across the space between the head d and the book Z, and presses it into place simply by the force of the air current. The valve may then be closed so that there will be no air flow either way, and at the same time the head d will be lowered to its lowermost position which will bring it in contact with the upper bearing blocks d² of the strip holder frame D'. After or during the described downward movement of head d the entire strip holder is moved or swung to the right by the cam D¹⁰, carrying it from the position seen in Fig. 2 to that seen in Fig. 3. In the meantime fibrous material has been fed into position beneath the knife F. Then the cam d⁴ operates to elevate the head d of the strip holder preferably until it pinches or presses the fibrous material against the knife F. At this stage the cutting off of the strip is effected, during or after which the cam e⁸ actuates the valve E to connect the strip holder interior with the exhaust and cause the strip to adhere to the upper surface of the head d. This action is continued through the following operations up to the time that the air is reversed for propelling the strip into contact with the book. The head d is then lowered by the cam d⁴ so as to separate it from the knife F, the strip y being carried with the head d, and thereupon the entire strip holder is by the cam D¹⁰ swung from the position of Fig. 3 to the left until it becomes substantially vertical, thus bringing the head d immediately beneath the book Z, it being understood that the book previously operated upon has been carried away and a new one, properly covered with adhesive at its lower edge, substituted. During or immediately following this swinging movement the cam d⁴ again comes into operation to cause the elevation of the head d from its lowermost position to its highest position, namely that seen in Fig. 2, after which the valve E is actuated to cut off the exhaust and admit a puff or flow of compressed air so as to propel the strip against the book, thus completing the cycle of operation. It should be stated that the blocks d² carrying the rollers d⁵, which coöperate in the raising and lowering of the head d, are ad-

justable upon the rods d' to permit the operative positions of the head d to be varied.

It will be seen that by reason of the construction above shown and described a book

5 binding machine is provided which answers the objects and affords the advantages of the invention as hereinbefore set forth; and other advantages will be apparent to those skilled in the art.

10 It is to be understood that the invention in its broader aspects is not limited to the precise construction shown nor to any particular construction by which the invention has been or may be carried into effect, since 15 many changes may be made in the details of the parts without departing from the main principles of the invention and without sacrificing its chief advantages.

What I claim as new and desire to secure 20 by Letters Patent, is:

1. A book-binding machine including in combination a book-positioning device for holding a book to which adhesive has been applied, a strip holder located adjacent a 25 book in said holder while a strip is being applied thereto, and an instrumentality for impelling a strip across the space from said strip holder to the book, said strip holder and impelling instrumentality being of such 30 character and construction as to be at all times spaced from the book; whereby said strip holder and impelling instrumentality are maintained free from adhesive.

2. A book binding machine, including in 35 combination means for positioning a book to which adhesive is applied, and means for impelling fibrous material to the book by air flow.

3. A book binding machine including in 40 combination a strip holder, a book holder adapted to be located closely adjacent said strip holder during the application of the strip to the book, and a pneumatic means for causing an air flow directed for impelling 45 a strip from said strip holder to an adhesive covered book in said holder.

4. A book binding machine, including in 50 combination a hollow strip holder having a series of orifices, and pneumatic means acting through the hollow interior to produce air jets for impelling a strip from said strip holder to an adhesive covered book.

5. A book binding machine, including in 55 combination a hollow strip holder, pneumatic means acting through the hollow interior for impelling a strip from said strip holder to an adhesive covered book, mechanism for causing successive strips to be placed in impelling position, a valve for 60 controlling air flow between said support and an exterior source, and a valve operating means actuated by said mechanism.

6. A book binding machine, including in 65 combination a strip holder, means for moving it to and fro between strip receiving

and applying positions, and means acting at strip applying position for impelling a strip from said strip holder to an adhesive covered book.

7. A book binding machine, including in 70 combination a hollow strip holder, means for moving it to and fro between strip receiving and applying positions, and pneumatic means acting at the strip applying position through the hollow interior for impelling a strip from said strip holder to an adhesive covered book. 75

8. A book binding machine including in combination means for holding a book to which adhesive is applied, a strip holder, 80 mechanism for causing lateral movements of the strip holder to and from strip receiving position and also movements toward and from the book whereby it may be brought to a position spaced apart from the 85 book, and means for impelling a strip from the strip holder to the book across the space therebetween.

9. A book binding machine including in combination a strip holder fitted for lateral vibratory movements and up and down movements, mechanism for causing said holder to vibrate laterally and to move up and down in harmony therewith, and means for adjusting the extent of up and down 95 movements.

10. A book binding machine including in combination a strip holder fitted for lateral vibratory movements and up and down movements, mechanism for causing said holder to vibrate laterally between strip receiving and applying positions and to move upwardly at applying position into proper relation to the book. 100

11. A book binding machine including in 105 combination a strip holder fitted for lateral vibratory movements and up and down movements, mechanism for causing said holder to vibrate laterally between strip receiving and applying positions and to move upwardly at applying position into proper relation to the book, and to move upwardly at receiving position to coöperate with an opposed member for receiving a strip. 110

12. A book binding machine, including in combination a hollow strip holder having means for moving it to and from strip applying position, a flexible tube connecting said hollow strip holder to an exterior source of compressed air in all positions of the holder, driving mechanism for actuating said holder moving means and a controlling valve automatically operated from said driving means. 115

13. A book binding machine, including in 120 combination means for holding an adhesive covered book, a movable strip holder constructed and fitted to be at all times spaced from said book holding means, suction means for holding a strip on said holder 125

until applied to the book, and means for impelling a strip across the space from said strip holder to the book.

14. A book binding machine, including in combination means for holding an adhesive covered book, a movable strip holder constructed and fitted to be at all times spaced from said book holding means, and pneumatic means for first holding a strip on said holder by an inflow of air and then impelling a strip across the space from said strip holder to the book by an outflow of air.

15. A book binding machine, including in combination means for holding an adhesive covered book, a hollow movable strip holder constructed and fitted to be at all times spaced from said book holding means, pneumatic means acting through the hollow interior for first holding a strip on said holder by an inflow of air and then impelling a strip across the space from said strip holder to the book by air outflow, and a valve for controlling air flow in both directions between said support and an exterior source.

25 16. A book binding machine, including in combination means for holding an adhesive covered book, a hollow movable strip holder constructed and fitted to be at all times spaced from said book holding means, means for moving it to and fro between strip receiving and applying positions, and pneumatic means acting through the hollow interior for first holding a strip on said holder by an inflow of air and then impelling a strip across the space from said strip holder to the book by air outflow.

17. A book binding machine including in combination a book holding device for supporting an adhesive covered book, a movable strip holding and repelling instrument, means for moving said instrument to and fro between a position adjacent to but spaced from the book and a strip receiving position, and means for supplying strips to said instrument at receiving position; whereby each strip may be held on said instrument until adjacent the book and then impelled to the book.

50 18. A book binding machine including in combination a book holding device for supporting an adhesive covered book, a pneumatic movable strip holding and repelling instrument, means for moving said instrument to and fro between a position adjacent to but spaced from the book and a strip receiving position, and means for supplying strips to said instrument at receiving position; whereby each strip may be pneumatically held on said instrument until adjacent the book and then pneumatically impelled to the book.

65 19. A book binding machine including in combination a book holding device for supporting an adhesive covered book, a pneumatic movable strip holding and repelling

instrument, means for moving said instrument to and fro between a position adjacent to but spaced from the book and a strip receiving position, and means for supplying strips to said instrument at receiving position by cutting such strips while such strips are engaged by said instrument; whereby each strip may be pneumatically held on said instrument until adjacent the book and then pneumatically impelled to the book.

70 20. A book binding machine including in combination a movable strip holding and repelling instrument, a strip cutting device, and a single machine part having connections for first, moving said instrument to a position adjacent the cutting device, second, operating the cutting device, third, moving said instrument to a position spaced from the book, and fourth, impelling the strip across the space from said instrument to the book.

80 21. A book binding machine including in combination a movable strip holder, means for impelling a strip from said holder, a strip cutting device, and a single machine part having connections for first, moving said instrument to a position adjacent the cutting device, second, operating the cutting device, third, moving said instrument to a position spaced from the book, and fourth, impelling the strip across the space from said instrument to the book.

90 22. A book binding machine, including in combination a movable member adapted to support a strip of fibrous material, a material feeding device, a strip cutting device, and a single machine part, having connections for first, moving said member to a position adjacent the cutting device, second, moving said member into contacting engagement with the material edge, third, operating the cutting device, and fourth, moving the member back to carry the strip to applying position.

100 23. A book binding machine, including in combination a movable strip holder having air passages, pneumatic means of producing air flow therein, and a single machine part, having connections for first, moving said holder to strip receiving position, second, moving the holder to strip applying position, spaced from the book, and third, causing said pneumatic means to produce air outflow to impel the strip across the space between the holder and book.

105 24. A book binding machine, including in combination, means for holding a book in proximity to a strip holder, a movable strip holder having air passages, pneumatic means of producing air flow therein, and a single machine part, having connections for first, moving said holder to strip receiving position and causing said pneumatic means to produce air inflow, second, moving the holder to strip applying position spaced

from the book, and third, causing said pneumatic means to terminate the air inflow; whereby the strip may be impelled across the space from the holder to the book.

5 25. A book binding machine, including in combination a movable strip holder having air passages, pneumatic means of producing air flow therein, and a single machine part, having connections for first, moving said 10 holder to strip receiving position and causing said pneumatic means to produce air inflow, second, moving the holder to strip applying position spaced from the book, and third, causing said pneumatic means to 15 terminate the air inflow and produce air outflow.

20 26. A book binding machine, including in combination a to and fro moving strip holder, a head movable up and down on said holder, a strip furnishing means and a single machine part, having connections for first, moving said holder to strip receiving position, second, raising said head to said strip furnishing means, and third, moving 25 said holder and head back to strip applying position.

27. A book binding machine, including in combination a to and fro moving strip

holder, a head movable up and down on said holder, a strip cutting device, and a single machine part, having connections for first, moving said holder to strip receiving position, second, raising said head to said strip cutting device, third, operating said device to cut a strip, and fourth, moving said 35 holder and head back to strip applying position.

28. A book binding machine, including in combination a to and fro moving strip holder, a head movable up and down on said 40 holder, a strip cutting device having a blade, and a single machine part, having connections for first, moving said holder to strip receiving position, second, raising said head to press a strip between said blade and head, 45 third, operating said device to cut off such strip, and fourth, moving said holder and head back to strip-applying position.

In testimony whereof, I have signed my name to this specification, in the presence 50 of two subscribing witnesses.

ALFRED BREDENBERG.

Witnesses:

JAS. AVERITT, Jr.,
JOHN LINDER.

It is hereby certified that in Letters Patent No. 1,129,064, granted February 23, 1915, upon the application of Alfred Bredenberg, of Champlain, New York, for an improvement in "Bookbinding-Machines," errors appear in the printed specification requiring correction as follows: Page 3, line 5, for the word "improper" read *proper*; page 4, lines 41-43, cancel the words and reference-letters "open exhaust pipe E', and surface e^{11} holds the valve in position to"; same page, line 94, for the word "roller" read *rollers*; and that the said Letters Patent should be read with these corrections therein that the same may conform to the record of the case in the Patent Office.

Signed and sealed this 23rd day of March, A. D., 1915.

[SEAL.]

J. T. NEWTON,

Acting Commissioner of Patents.
